UNITED STATES PATENT OFFICE.

HARRY ELLWOOD SLOAN, OF PHILADELPHIA, PENNSYLVANIA.

TYPE-TURTLE OR FUDGE-BED FOR ROTARY PRINTING-PRESSES.

1,316,337.

Specification of Letters Patent. Patented Sept. 16, 1919.

Application filed January 18, 1919. Serial No. 271,876.

To all whom it may concern:

Be it known that I, HARRY ELLWOOD SLOAN, a citizen of the United States, residing at Philadelphia, in the county of Philadelphia and State of Pennsylvania, have invented a new and useful Type-Turtle or Fudge-Bed for Rotary Printing-Presses, of which the following is a specification.

The present invention relates to a type-turtle or fudge-bed such as is shown and described in Patent Number 1,052,678. While generally stated such a type-turtle or fudge-bed is admirably adapted for the purpose intended practice has dictated that the arrangement disclosed in said patent for locking type-slugs with respect to a type-turtle possesses certain disadvantageous features. By the arrangement shown in said patent the type-slugs are collectively retained in place by means of a resiliently held head. When it is desired to remove a single type-slug withdrawal of the head obviously serves to release all of the type-slugs. Frequently the position of a printing cylinder, as stopped for the change of type-slugs, is such that with the withdrawal of said head type-slugs, other than the one desired to be removed, drop from the type-turtle. Since the saving of time and quick results are of the essence of printing late news inserts, the importance of overcoming the above described disadvantageous feature is apparent.

This invention has for an object to remedy the above described defect and provide a locking head construction in which type-slugs may be selectively released in contradistinction to being collectively released. Other and further objects relate to the provision of certain new and novel arrangements, combinations and connections of parts as will hereinafter more fully appear.

With these and other objects in view the invention consists of the improvements hereinafter described and finally claimed.

The nature, characteristic features and scope of the invention will be more fully understood from the following description taken in connection with the accompanying drawings forming part hereof, and in which:

50 Figure 1, is a top or plan view of a type-turtle or fudge-bed embodying features of the invention.

Fig. 2, is a view in longitudinal section taken upon the line 2—2 of Fig. 1, and

55 Fig. 3, is a view in transverse section taken upon the line 3—3 of Fig. 2.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring now to the drawings 10 designates the bed-piece secured to which as by screws 11 and 12 are the end plates 13 and 14, of which the end plate 14 has a serrated inner face 15, see Fig. 2. Connecting the end plates are side-plates 16. Within the space formed by the end and side-plates and bed-piece is adapted to be contained the various type and type-slugs for making up a late news insert. The manner in which the type and type-slugs are spaced and positioned forms no part of the present invention and is fully described in the aforesaid patent so that description thereof herein is unnecessary except to state that 17 and 18 designate notched type and type slugs respectively which are retained in printing position by means of endwise shiftable latches 19 for the lateral engagement of said type and type-slugs and that 20 designates unnotched type-slugs which in practice are locked with respect to the type-turtle or fudge-bed independently of the notched type and notched type-slugs. The reason for the independent locking thereof is that notched type are calculated to be constantly changed while the unnotched type-slugs are only changed at infrequent intervals. A description will now be given of my improved means for retaining in printing position the unnotched type-slugs 20. The end plate 13 is bored longitudinally as at 21 to accommodate endwise shiftable rack-bars or toothed bolts 22 of which there are three although the number may be increased or diminished if found desirable. Extended rearwardly from each rack-bar is a stem 23 which projects through an aperture in the rear wall of the end plate and a spring 24 is coiled around said stem and between the rear wall of the end plate and a rack-bar for normally impelling such bolt forward. The free end of a rack-bar is notched to receive a horizontally disposed grip 25 having a

95

100

105

110

knife edge for the longitudinal engagement of a type-slug 20. Such engagement of a type-slug forces it against the serrated face of end-plate 14. End-plate 13 is cut away 5 as at 26 to accommodate a grip 25 in the rearward movement of a rack-bar. The grips are made sufficiently wide so as to engage several type-slugs if necessary as shown at the upper part of Fig. 1. For shifting a 10 rack-bar a tool is employed comprising a stem 28 having an enlarged toothed periphery 29 and an operating handle 30. To permit engagement of the tool with a rack-bar the end plate 13 is vertically drilled as at 15 31 adjacent each horizontal bore and is in communication therewith so that the toothed portion of a rack-bar may project into a vertically drilled portion. Thus the toothed portion of the tool as inserted within a vertically drilled portion of the end-plate 13 20 co-operatively engages with the teeth of a rack-bar so that partial rotation of the tool around its vertical axis serves to move a rack-bar, against the pressure of spring 24, 25 away from that part of the type-turtle or fudge-bed occupied by the type and type-slugs. The lower part of each of the vertically drilled portions of the end-plate 13 is drilled slightly smaller in diameter as at 31' 30 to accommodate the lower end 32 of the tool. Such drilled portion 31 serves to center the tool with respect to a rack-bar and also serves as a bearing for said tool. From the above description it is apparent that a single 35 type or type-slug and one in immediate juxtaposition thereto may be removed from a type-turtle or fudge-bed without interfering in any way with such other type-slugs as may be in the type-turtle.

40 40 It will now be apparent that I have devised a novel and useful construction which embodies the features of advantage enumerated as desirable in the statement of the invention and the above description and while 45 I have in the present instance shown and described the preferred embodiment thereof which has been found in practice to give satisfactory and reliable results, it is to be understood that the same is susceptible of 50 modification in various particulars without departing from the spirit or scope of the invention or sacrificing any of its advantages.

What I claim is:

1. A type-turtle constructed to receive 55 type and type-slugs the shanks of which are notched laterally and also to receive type-slugs having unnotched shanks, means for laterally engaging with a series of notched shanks of said type and type-slugs to interlock same with respect to the type-turtle, and a plurality of resiliently held 60 mediums for individually engaging in a longitudinal manner the said unnotched type-slugs to interlock same with respect to the type-turtle independently of the notched 65

type and type-slugs, said mediums being adapted for engagement by a suitable tool, whereby each of them may be operated independently of all the others.

2. In a type-turtle a fixed end-plate provided with a plurality of resiliently held endwise shiftable bolts equipped with type-slug engaging bits, said bolts being adapted for engagement by a suitable tool, whereby each of them may be operated independently of all the others. 70

3. In a type-turtle a fixed end plate provided with a plurality of resiliently held endwise shiftable rackbars equipped with type-slug engaging bits, said rack-bars being adapted for engagement by a suitable tool, whereby each of them may be operated independently of all the others. 80

4. In a type-turtle a fixed end-plate provided with a plurality of resiliently held endwise shiftable rackbars equipped with type-slug engaging bits, a vertically disposed cylindrical socket in said end-plate adjacent each rack-bar and into which opening the teeth of a rack-bar project said socket being 85 adapted to receive a tool for engaging the teeth of a rack-bar whereby each rack-bar may be moved independently of all the other rack-bars. 90

5. In a type-turtle a fixed end plate provided with a plurality of resiliently held endwise shiftable bolts and a horizontally disposed type-slug engaging bit having a knife edge fixed to each bolt which bits are relatively broad laterally considered each 100 bolt being adapted to be operated independently of all the other bolts. 95

6. A type-turtle adapted to receive type and type-slugs, means for laterally engaging a group thereof to interlock same with respect to the type-turtle and a plurality of resiliently held members for engaging in a longitudinal manner certain others thereof to interlock same independently of a group 105 said members being adapted to be engaged by a suitable tool whereby each of said members may be shifted independently of all the other members. 110

7. A type-turtle adapted to receive type and type-slugs, means for laterally engaging 115 a group thereof to interlock same with respect to the type-turtle and a plurality of resiliently held endwise shiftable members for engaging certain others thereof to interlock same independently of a group 120 said members being adapted to be engaged by a suitable tool whereby each of said members may be shifted independently of all the other members.

8. A type-turtle adapted to receive type and type-slugs, means for laterally engaging a group thereof to interlock same with respect to the type-turtle and a plurality of resiliently held endwise shiftable members each provided with a bit for engaging cer- 125 130

tain others thereof to interlock same independently of a group said members being adapted to be engaged by a suitable tool whereby each of said members may be shifted independently of all the other members.

9. A type-turtle adapted to receive type and type slugs, means for laterally engaging a group thereof to interlock same with respect to the type-turtle and a plurality of 10 resiliently held endwise shiftable members each provided with a bit having a knife edge for engaging certain others thereof to interlock same independently of a group said members being adapted to be engaged by a 15 suitable tool whereby each of said members may be shifted independently of all the other members.

10. A type-turtle having a fixed plate provided with a plurality of resiliently held 20 endwise shiftable type or type-slug engaging members said members being adapted to be engaged by a suitable tool whereby

each of said members may be shifted independently of all the other members.

11. A type-turtle having a fixed plate 25 provided with a plurality of resiliently held endwise shiftable members each provided with a type or type-slug engaging bit said members being adapted to be engaged by a suitable tool whereby each of said members 30 may be shifted independently of all the other members.

12. A type-turtle having a fixed plate provided with a plurality of resiliently held endwise shiftable members each provided 35 with a bit having a knife edge said members being adapted to be engaged by a suitable tool whereby each of said members may be shifted independently of all the other members.

In testimony whereof I have hereunto signed my name.

HARRY ELLWOOD SLOAN.
